UNITED STATES PATENT OFFICE.

GEORG HERRMANN, OF RIVER ROUGE, MICHIGAN.

STANDARD FOR ELECTRIC WIRING AND SUPPORTS THEREFOR.

Application filed December 29, 1926. Serial No. 157,718.

This invention relates to improvements in standards for electric wiring and supporting means therefor.

It is an object of the invention to provide a strong rigid standard that will withstand storms, cannot rust, will last indefinitely, will not be damaged by fire or water, and can be cheaply manufactured.

Another object of the invention is to provide a standard and supporting means so designed that when the latter has been placed in position in the ground the former may be readily inserted into the support and securely held in position. Moreover at any subsequent time the standard may be quickly removed from its support if for any reason it is desired to change the location of the standard.

A further object of the invention is to provide a standard wherein the possibility of its being damaged by lightning is reduced to a minimum.

With these and other objects in view which will become apparent as the specification proceeds, the invention is herein-after more fully described with the aid of the accompanying drawings and claimed.

Figure 1 is a side elevation of the standard and supporting means partly in section. Figures 2, 3 and 4 are sections on the lines 2—2, 3—3 and 4—4 of Figure 1.

Figure 5 is a detail of one of the clamp rings showing part of the wire reinforcing supported thereby.

Referring to the drawings, 1 designates a standard consisting of a concrete post longitudinally through the centre of which is a metal rod 2. The latter extends beyond the upper end of the standard to receive a conventional lightning conductor 3, and the said rod terminates at its lower end substantially flush with the underside of the post. The ground level is indicated at 4. In the standard shown in the drawings that portion which is above ground is shown circular, and the portion below ground is of octagonal section, but obviously the cross sectional shapes may be made to suit requirements.

Around the rod 2 at intervals clamp rings 5 are secured. These clamp rings are insulated from the rod 2 by any suitable non-conducting material such as the sheet asbestos rings shown at 6. Through the clamp rings are a plurality of peripheral holes 7. Wires 8, 8^a and 8^b are threaded

through the holes 7, pass substantially radially outwards towards the periphery of the standard and their outer portions 8^d are of such shape as to conform to the periphery of the standard within which they are located. These wires constitute a very light and yet strong form of reinforcing for the posts, and may be spaced at any desired interval apart according to the size and weight of the standard.

Substantially parallel with the sides of the standard a plurality of substantially vertical wires 9 are arranged. These wires 9 extend from the lower wire 8^a to the upper wire 8^b to which they are attached, and they are also looped around each of the intermediate wires 8 in turn. A collar 10 is secured around the rod 2 and insulated therefrom as by asbestos 11. From this collar and usually integral with it are a plurality of radiating arms 12.

The support 13 which is also made of concrete has a hole 14 extending downwardly therein from the top to receive the lower end of the standard. The bottom of the hole 14 is preferably tapered downwards towards the centre as shown at 15 and the underside of the standard is similarly shaped to rest therein. Through the underside 16 of the support a pin 17 is inserted which is longer than the thickness of the said underside so that its lower end will enter the ground 28 in which the support is sunk. The upper end of the pin has a head 18 thereon which is substantially flush with the bottom of the hole 14 so that the lower end of the rod 2 will rest thereon. In this manner a good earth connection is made directly from the lightning conductor 3, and the insulation 6 and 11 insure any electricity from the conductor passing only to earth.

At the upper end of the support 13 the hole 14 is larger and tapers downwards, and in the sides of the hole 14 slots 19 are provided to receive the arms 12. A wedge-shaped ring 20 preferably having hooks 21 in its upper side firmly holds the standard in position in its support when driven down into the tapered portion of the hole 14.

The standard is grooved circumferentially at 22 to receive the clamping member 23 which is secured as by bolts 24. On the member 23 is a cross arm 29 generally reinforced by braces 25. These braces and the cross arm may be made integral with the

clamping member or may be welded or otherwise secured to the latter.

On the cross arms 29 conventional insulators 26 are supported as by nuts 26^a to receive electric wires. Obviously when desired extra cross arms may be mounted on the standards if it is desired to carry more wires than one cross arm will support.

The support 13 is preferably reinforced 10 as shown at 27 to render it less liable to breakage when being moved from place to place.

While in the foregoing the preferred embodiment of the invention has been described 15 and shown it is understood that the invention is subject to such modifications as fall within the scope of the appended claims.

What I claim as my invention and desire 20 to secure by Letters Patent is:

20 1. In a standard for electric wires and a support therefor, the combination of a concrete post having a rod extending longitudinally and substantially therethrough, a collar secured around said rod, radiating arms 25 on said collar, said support having a hole therein to receive the lower end of said post and slots to receive said radiating arms, and a wedge-shaped ring to support said post in the hole in said support.

30 2. An arrangement of the character described, comprising a concrete post having a rod extending longitudinally therethrough and projecting above said post, a lightning conductor secured to the upper end of

35 said rod, clamp rings around said rod and insulated therefrom, lateral reinforcing secured to said clamp rings, and vertical reinforcing supported by said lateral reinforcing, in combination with a support adapted 40 to be sunk in the ground and having a vertical opening therein to receive the lower end of said post, a pin through said support on which the lower end of said rod rests, the lower end of said pin projecting below 45 said support and being adapted to enter the ground, and a removable wedge-shaped ring around said post adapted to hold the latter in a substantially vertical position in said hole.

3. An arrangement of the character described comprising a concrete post having a rod extending longitudinally therethrough and projecting above said post, a lightning conductor on the upper end of said rod, reinforcing in said post, and supporting 50 means secured around said rod and insulated therefrom to hold said reinforcing, in combination with a support adapted to be sunk in the ground and having a hole therein to receive the lower end of said post, a pin 55 through said support extending below the latter and adapted to project into the ground, the lower end of said rod being adapted to rest on said pin, and removable means around said post for holding the latter 60 in a substantially vertical position in the hole in said support.

GEORG HERRMANN.
